Patented Jan. 28, 1890

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,612, dated January 28, 1890.

Application filed December 26, 1889. Serial No. 335,073. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

The leading feature of my design consists of entwining ribbons forming square figures 1, having in the center a button 2. Surrounding the general figure radiate branching scrolls 3, between which at each side of the square is an oblong rosette 4. The inter-

vening space between the last-mentioned figures is filled in with other entwining ribbon ornaments 5, having a plain button in the center.

The groundwork of design is filled in with line-work and ornamented with plain buttons. 20

What I claim is—

The design for a wall and ceiling covering herein shown and described, consisting of entwining ribbon square ornaments, diamond-shaped ribbon ornaments, branching scrolls, 25 and buttons.

PAUL GROEBER.
